BY Victor J. Evans

ATTORNEY

UNITED STATES PATENT OFFICE.

RAY SMITH, OF DAYTON, OHIO.

FUSE.

1,261,636.

Specification of Letters Patent. Patented Apr. 2, 1918.

Application filed March 2, 1917. Serial No. 152,031.

To all whom it may concern:

Be it known that I, RAY SMITH, a citizen of the United States, residing at Dayton, in the county of Montgomery and State of Ohio, have invented new and useful Improvements in Fuses, of which the following is a specification.

This invention relates to improvements in multiple fuses for electric circuits.

10 The objects of this invention are to provide a multiple fuse wherein the fuse elements may be readily replaced; and to provide in such a fuse for the utilization of fuse elements having a portion whereon the capacity of the elements may be conveniently indicated, and further to render impossible the use in this plug of fuse elements not manufactured especially therefor.

With these and other objects in view which will appear upon examination of the accompanying drawings, specification and claims, I have embodied my invention in the form shown and described therein.

In the drawings,

25 Figure 1 is a side view showing the exterior of the fuse.

Fig. 2 is a sectional side view of the fuse.

Fig. 3 is an end view of the fuse with cap removed.

30 Fig. 4 is an end view of the opposite extremity of the fuse-containing body.

Fig. 5 is an end view of the plug forming a portion of the fuse showing the end adapted to be mounted adjacent to said body.

35 Fig. 6 is a detailed view of one means for securing the replaceable fuse elements in position.

Referring now to the drawings in detail, 40 1 is a plug of insulating material, having secured thereto a brass collar 2 with threads adapted to engage those of the fuse receptacle. Collar 2 is connected by a suitable conductor with a spring actuated pin 3, 45 protruding from the opposite end of the plug and off-center thereof. At the end of the plug where the pin is inserted is an enlarged cylindrical portion 9 around the circumference whereof is located a plurality of spaced notches 4. Centrally located and longitudinally extending through said plug is a bore or hole 5, having a counter-bore or enlargement 6 at the end of the plug intended for insertion in a fuse receptacle.

50 Adjacent to the pin end of plug 1 is a cylindrical body 7 of insulating material,

serving the purpose of a fuse magazine. At the plug end of said body is a circular recess 8, adapted to receive the cylindrical portion 9 of the plug 1 and having suitably disposed 60 around the wall of said recess a plurality of longitudinal ridges 10 adapted to engage the notches in cylindrical portion 9. Centrally positioned and longitudinally extending through body 7 is a bore 11. Concentrically disposed with relation thereto is an annular series of longitudinal bores 12, having at the plug end of said body counter-bores or enlarged portions 13. Into these bores are inserted the replaceable fuse elements 14, having heads 15 of suitable size and shape for insertion in the counter-bores 13, the fusible portions attached thereto extending through bores 12 into a recess 17 at the opposite end of the body. In each of the heads 15 is a 70 depression 18, adapted to receive the pin 3 on plug 1.

The fusible portions projecting into recess 17 are bent parallel to the inner face of said recess and securely clamped thereto by a circular plate 19 about the circumference of which are spaced notches 20 adapted to coincide with the longitudinal ridges 21 corresponding to the ridges 10 in recess 8. Centrally positioned in plate 19 is a hole 22, 80 having threads therein adapted to engage the threads at the extremity of a screw shank 23 of conducting material, extending through bore 11 in body 7 and bore 5 in plug 1, and at the extremity adjacent to said plug the shank has a head 24 adapted to establish connection with a central electrode of a fuse receptacle, and further serving the purpose of retaining in position a spring 25, situated in counter-bore 6 in said plug, said 85 spring maintaining body 7 in contact with plug 1.

In contact with plate 19 is a similar plate 26, having however, an enlarged hole in the center which is not provided with screw 100 threads. Plate 26 is provided with notches similar to those on plate 19 and also engaging the longitudinal ridges 21. A helical compression spring 27 is maintained in position against plate 26 by a cap 28 of insulating material provided with screw threads by which it is securely attached to similar threads around the outer end of body 7.

From the above description it will be readily seen that one of fuse elements 14 is 110 always included in a circuit attached to a fuse receptacle in which this fuse may be

inserted. Upon one of the fuses becoming burnt out, it is merely necessary to withdraw body 7 against the tension of spring 25 until the ridges 10 no longer engage notches 4. 5 Upon a slight rotation of body 7, ridges 10 will again register with the notches in a different position, thereby enabling pin 3 to establish contact with an undamaged fuse element. Upon all of the fuse elements in 10 body 7 having been used, the screw shank 23 is withdrawn from the bore by means of the slot in the head thereof adapted to receive a screw-driver, thereby permitting the separation of the body and plug. Cap 28 now 15 being unscrewed, spring 27 and plates 26 and 19 may be removed, thereby permitting ready insertion of a new set of fuse elements.

For certain purposes I may construct body 7 of insulating material, capable of being 20 shaped in a die, and in this connection may utilize the construction shown in Fig. 6, wherein the enlargements 13 of bores 12 in body 7 are provided with metal pockets knurled or otherwise roughened outside, and 25 which may be incorporated in said body when shaped in said die. These pockets are provided with screw threads in the inside thereof, adapted to engage similar threads which I may place on the heads 15 of the 30 fuse elements 14, these heads in this instance being provided with a slot whereby they may be readily inserted in or removed from said pockets, thereby providing an extremely 35 secure method of securing the replaceable elements in position.

It is well known to those having occasion to use replaceable fuses, that the fusible wires constituting fuses of different capacity, as ordinarily constructed, are exceedingly difficult to distinguish one from another.

The above drawings and specification describe a preferred form of my invention for purposes of illustration, but I wish it to be 45 understood that said drawings and specification are not to be interpreted as in any way limiting the scope of my invention; as many other embodiments may be constructed without departing from the spirit or scope 50 thereof.

What I claim is:

1. In a device of the class described, the combination with a relatively fixed plug having an off-center spring-pressed pin, a

relatively rotatable body having an annular 55 series of bores adapted to be brought successively into register with the pin and a recess in its outer end, and a cap removably closing said recess; of fuses in said bores and having their outer ends extending into 60 said recess, a plate overlying such ends, expansive means between it and the cap, a screw passing axially through said plug and body and threaded into the plate, the head of the screw forming a central terminal, and 65 a collar on the plug connected with the pin and forming the other terminal.

2. In a device of the class described, the combination with a relatively fixed plug having an axial hole counter-bored at its 70 outer end, an off-center pin in said plug, a relatively rotatable body coaxial with the plug and having a series of off-center bores adapted to be brought successively into register with the pin, fuses in said bores having 75 heads at their inner ends to contact with said pin, and a plate at the outer end of the body overlying the outer end of said fuses; of an expansive spring in the counter-bore of the plug, a screw passing therethrough and through the axis of the body and removably engaging said plate, the head of the screw forming the central terminal of the device, and a collar on the plug connected with the pin and forming the other 80 terminal.

3. In a device of the class described, the combination with the stationary element of the device and the revoluble body formed at one end with a ridged recess and further 90 formed with a plurality of fuse-holding bores opening into said recess, of fuse elements seated in said bores and having bent ends projecting into said recess, a conducting plate seated in said recess against said 95 ends of the fuse elements, said plate formed centrally with a screw threaded opening and formed with notches for engaging with said ridges of the recess, a shank extending through said stationary element and said body and having screw threaded engagement in said opening, a cap screw threaded on the body over said recess, and a spring in said recess bearing against said cap and said plate.

In testimony whereof I affix my signature.

RAY SMITH.
